Primary Examiner — Philip S Hyder*Assistant Examiner* — Roselynne Cody(74) *Attorney, Agent, or Firm* — Gottlieb, Rackman & Reisman, P.C.(57) **CLAIM**

The ornamental design for a utility knife, as shown and described.

DESCRIPTION

FIG. 1 is a front, top and right side perspective view of the utility knife showing our new design;

FIG. 2 is a left side elevational view thereof;

FIG. 3 is a top plan view thereof;

FIG. 4 is a front elevational view thereof;

FIG. 5 is a rear elevational view thereof; and,

FIG. 6 is a bottom plan view thereof.

The broken lines in FIGS. 1-6 are for illustrative purposes only and form no part of the claimed design.

1 Claim, 3 Drawing Sheets# US D682,065 S
